UNITED STATES PATENT OFFICE.

CHESTER A. MACOMIC, OF CHICAGO, ILLINOIS, ASSIGNOR TO PATENT PRODUCTS CORPORATION OF CHICAGO, OF CHICAGO, ILLINOIS, A CORPORATION OF DELAWARE.

PROCESS OF AND APPARATUS FOR TYPE CASTING AND PROOF READING.

Application filed May 6, 1925. Serial No. 28,292.

My invention relates to a process of type casting and for the means for carrying it out. It has for one object the provision of a process of and means for casting lines of type in response to the actuation of a typewriter key board. Other objects will appear from time to time in the course of the specification and claims.

My invention is illustrated more or less diagrammatically in the accompanying drawings, wherein:

- 5 Figure 1 is a vertical longitudinal section;
- 10 Figure 2 is a section along the line 2—2 of Figure 1;
- 15 Figure 3 is a perspective view of a matrix strip;
- 20 Figure 4 is a bottom view of such a strip;
- 25 Figure 5 is a horizontal section illustrating the alignment of the matrix strips with the controlling stops;
- 30 Figure 6 is a detail illustrating the engagement of the matrix strip with a controlling stop.

Like parts are indicated by like characters throughout the specification and drawings.

A is any suitable typewriter mechanism having a plurality of type controlling keys A¹ and a shift key A². The keys are all situated upon the ends of vertically disposed flat strips A³, as usual in typewriter practice, which strips pass through the slotted comb guide plate A⁴. A⁵ is any suitable adjusting means for adjusting the level of the typewriter in relation to the frame members B of the line of type machine.

Adapted to be controlled by each key, as the key is compressed is a key extension member B¹ which extends to one arm of the bell crank lever B², shown in dotted lines in Figure 1, and pivoted as at B³. To the opposite arm of the lever B² is pivoted as at B⁴ a controlling wire B⁵ the opposite end of which is secured to the upper edge B⁶ of a shutter B⁷ which is pivoted as at B⁸ and is provided with a downwardly turned lower edge B⁹. It will be understood that there is a key extension member, a bell crank-lever, a wire and a shutter for each key of the typewriter, each shutter extending transversely from side to side of the typewriter across substantially the entire width of the line of type casting machine.

Underlying the shutters is a plunger carriage C having mounted in it for vertical movement a plurality of plungers C¹ each

having the relatively extended head C² and a lower extension C³ of smaller cross section. It will be understood that the plunger carriage bears a plunger for each shutter.

I move the plunger carriage laterally in unison with the usual typewriter escapement carriage, by means the details of which form no part of the present invention. Thus the position of the plunger carriage corresponds with the position of that part of the escapement carriage which is to receive the next type impression, and, during the writing of a line of type on the typewriter, the plunger carriage travels laterally entirely across the bed of the machine.

Underlying the plunger carriage is a stop bed D in which are positioned for vertical movement a plurality of stops D¹. The stop bed D is mounted for vertical movement for example on the shafts D² which pass through the bearing members D³ and may be moved vertically, to move the stop bed, by any suitable mechanism, the details of which are not herein shown as they form no part of the present invention. The stops in the stop bed are arranged in lines lying parallel with the plunger carriage. In each line there are two stops for each plunger of the plunger carriage. There are as many lines of stops as there are spaces to be filled, in the line of type to be produced.

Each plunger controls two stops, through the longitudinal movement of the plunger carriage C by means of the connecting link E which is controlled by the shaft key E¹ of the typewriter and is pivoted to an arm of the bell crank lever E². The opposite arm of the bell crank lever is secured by means of the wire E³ to the lever arm E⁴ which rotates the shaft E⁵ and through it the arm E⁶ which in turn longitudinally moves the plunger carriage C.

The stops D¹ are depressed, through the shutters and the plungers C¹, half of the stops of each line being aligned with the plungers when the shift key is in the normal position, the other half being aligned with the plungers when the shift key is depressed.

In case the operator, seeing an error in proof which is typed by the normal typewriter mechanism wishes to correct it, he draws the roller G to the right, as shown in Figure 1, the roller being actuated by any suitable belt or chain G¹ which passes about

70

105

110

the sheaves G^2 G^3 . The roller pushes the stops up into the inoperative position, and the operator rewrites the line.

H is any suitable supporting bed or table 5 having the upper supporting surface H^1 . Longitudinally slidably upon this surface are a plurality of matrix strips H^3 , the details of which are shown in Figures 3, 4 and 10 6. Each matrix strip has a flat under surface H^4 which is penetrated by the vertically aligned symbols H^5 , each strip having aligned along it all the characters governed by or appearing on the keyboard used to operate the device. Preferably I arrange 15 these characters in pairs each adjacent pair being a pair of characters appearing on one of the typewriter keys.

At the forward end of each strip is an indentation H^6 , the forward wall H^7 of which 20 serves as a spring abutment. The forward end is bevelled as at H^8 . At the rear of the strip is an upwardly projecting stop H^9 which is forwardly continued along one side 25 of the strip as at H^{10} .

J is any suitable spring finger the downwardly inclined end J^1 of which is adapted 30 to engage the spring abutment H^7 . I do not illustrate in detail the means for drawing the spring finger J along the bed H but it will 35 be understood that any suitable means may be provided for engaging it with the spring abutment H^7 and for drawing the matrix strip to the left as shown in Figure 1.

K illustrates the casting throat, a trans- 35 verse slot extending from side to side of the bed H and adapted to receive a charge of molten metal which may be fed in any suitable manner not here shown in detail.

L is a suitable transverse yoke overlying 40 the matrix strips and adapted to be clamped downwardly against them, for example by means of the spiral springs L^1 , in their housings L^2 , which are pressed between the bottom of the table H and the pins L^3 on the 45 shafts L^4 , the shafts being secured to the ends L^5 of the yoke L , and passing through the table H . The yoke L may normally be held in slightly raised position to permit free longitudinal movement of the matrix strips, for 50 example through the links L^6 which may be held in relatively raised position by any suitable means not herein shown. The metal pot from which the type metal is forced into the throat is diagrammatically shown as at 55 L^7 .

M is any suitable abutment arm which may be adjusted about the pivot M^1 in the yoke L for example by the set of screws or bolts M^2 M^3 bearing against the arms M^4 M^5 . M^6 60 is an abutment strip bevelled as at M^7 and adapted to engage one of the compression strips M^8 , between which the matrix strips may be compressed. M^9 is the opposite abutment strip bevelled as at M^{10} and adapted 65 to be engaged by the lower arm of the

squeeze lever M^{12} which is pivoted as at M^{13} in the yoke L and has an upper arm M^{14} surrounding the vertical guiding bolt M^{15} held in normally raised position by the spiral compression spring M^{16} .

70

The use and operation of my invention are as follows:

I provide a type casting mechanism which may be operated by any suitable keyboard but which I prefer to operate by using an ordinary typewriter. The typewriter is positioned above or in front of the type casting mechanism and the positioning of the matrices of the type casting mechanism is governed by the keys of the typewriter keyboard. One outstanding advantage of this arrangement is that it is easy in proof reading. The operator writes a line on the typewriter, and can read that line on the paper in the usual way. When an entire line has 85 been correctly written, a slug is cast which reproduces it.

75

I use a separate matrix strip for each available space in each slug. Thus if I cast slugs having the width of eighty letters, I employ 90 a series of eighty matrix strips positioned side by side on a supporting bed. In the bottom of each matrix strip is the impression of every letter or character which can be printed. Thus by having matrix strips for each 95 space on the slug, and by having all the characters on each matrix strip, I can position any character at any point on the slug.

80

In order to avail myself of the typewriter mechanism, I provide key extension members, one of which is contacted by each key as the key is depressed in response to the pressure of the finger of the operator. Each such key extension member controls the movement of the matrix strip for the particular space along the line of type and along the slug which is being filled, when the key is depressed. In order to obtain this control I provide a transverse shutter or pressure transmitting member which extends transversely across the entire bed of the machine. Each shutter is pivoted and is controlled by a tension wire which in turn is secured to a bell crank lever, the opposite arm of which is controlled by the key extension member. 110 Thus at each key depression a shutter is depressed.

105

Underlying the shutters is the plunger carriage which has thereon a plunger aligned with each shutter. This plunger carriage 120 moves in unison with the movement of the typewriter escapement carriage, and always is aligned with the space on the slug which is being filled by the particular key pressure involved.

115

Positioned beneath the plunger carriage is a stop bed, in which are mounted rows of stops overlying each matrix strip. In each such alignment there are, with the Remington typewriter, for example, eighty three 125

130

stops, two for each of the forty-two keys with the omission of one stop for one character, the underscore, which is not used in type casting. When a key is depressed it 5 depresses a shutter, and the shutter depresses a plunger on the plunger carriage, and the plunger depresses a stop, the stops being frictionally mounted in the stop bed. In order to control all eighty-three stops with the 10 forty-two plungers which correspond to the forty-two keys I employ a connection with the shift key of the typewriter which, in response to movement of that key, rotates a bell crank lever, the opposite arm of which 15 is connected to the plunger carriage and moves it longitudinally. Each plunger having a relatively extended upper surface, the action of the shutters on the plungers is not affected by this longitudinal movement of 20 the plunger carriage and the plungers. However, it does affect the alignment of each plunger with the stops positioned beneath it, and I am thus able to control, when using a single shift typewriter key bar, two stops 25 with each plunger.

When the operator has written an entire line, he has depressed stops at various points all the way across the matrix supporting bed. He first corrects the line, if correction 30 is necessary, and he can do this by running a roller beneath the stops, which forces them back into inoperative position, he then writes the line over again. When the proof is correct, the operator depresses the stop 35 bed into such position that the stops are in longitudinal alignment with the upwardly projecting stops on the individual matrix strips. He then pushes the operating lever and draws all the matrix strips forward in 40 unison. Each strip is engaged at one end by a spring catch, which seats in a spring abutment. When the stop on each matrix strip engages the opposed stop on the stop bed, the matrix strip is arrested and the 45 spring catch frees it. When all the matrix strips are released from the springs they are all aligned with the desired characters overlying the casting point or throat. Where a space instead of a letter was used, a blank 50 portion of the matrix strip will overlie the casting point. When the matrix strips are all aligned the operator clamps or squeezes them laterally together, in order to prevent irregularities or displacements and then operates the pump which forces in the molten metal which fills the narrow space beneath the matrix strips to form a slug. This space is defined or closed by laterally and vertically movable elements, the details of which 55 are not of importance in the present application, but which can be moved to free the slug after it is cast and to permit it to be delivered to any suitable rack or conveying means. After each such casting operation 60 the matrix strips are moved back to their

original position ready for the writing of a new line of type.

While I have illustrated a device which may be and preferably is used with a typewriter, it will be obvious that I might obtain the same result with many varieties of keyboard and that I might, under some circumstances, depart from the use of a typewriter or its equivalent. However in practice it has proved advantageous to use a typewriter and to use typewriter paper as a positive check in proof reading, a check which is operative before the slug is cast and which effects an enormous saving in time and in material. No line of type is cast until its proof has been read and corrected.

I claim:

1. The process of type casting from matrices, including the steps wherein the setting of the selecting means for the matrices is responsive to the impression of a visual counterpart of the type to be cast, and wherein the final positioning of the matrices is made after the correction of the 85 visual counterpart.

2. The process of casting type from a plurality of matrices each having a plurality of type impressions, which consists in preparing selecting means for the impressions and making a visual counterpart of the impressions, then proving the impressions by observation of the visual counterpart, then setting the matrices with the proved impression on each positioned in a casting zone, and positioning thereagainst the type forming 95 material.

3. The process of casting type from a plurality of matrices each having a plurality of type impressions, which consists in preparing selecting means for the desired impressions successively in each line, making a visual counterpart of each impression as selected, proving the selection of the impression by observation of the counterpart, and, after such proving, simultaneously casting 100 the impressions of the line.

4. The process of casting type from a plurality of matrices each having a plurality of type impressions, which consists in successively selecting characters, proving the characters successively as selected, then moving the matrices to position corresponding impressions of each matrix in a casting zone, and simultaneously casting a plurality of corresponding printing characters.

5. The process of casting type from matrices which includes selecting in succession the desired printing characters and forming a visual counterpart of each character as it is selected, and at the same time positioning control means for the corresponding matrix, and subsequently, after a plurality of such selections simultaneously moving a plurality of matrices, to position the characters so selected in a casting zone, and subsequently 125 130

simultaneously casting the impressions so positioned.

6. The process of casting type from matrices which includes selecting in succession the desired characters and forming a visual counterpart of each character as it is selected, and at the same time positioning control means for the corresponding matrix, and subsequently, after a plurality of such selections, moving the matrices to position the impressions so selected in a casting zone, and subsequently casting the impressions so positioned.

7. The process of casting type from a plurality of matrices, each having a plurality of type impressions, which consists in successively selecting the characters to form a single line, proving the impressions of such characters successively as selected, subsequently moving the matrices to position the desired impressions in a casting zone, and simultaneously casting the impressions forming such line.

8. The process of casting type from a plurality of matrices, each having a plurality of type impressions, which consists in successively selecting the characters to form a single line, making a visual counterpart of each character as selected, proving the selection of the characters by observation of the counterpart, moving the matrices to position the desired impressions in a casting zone, and simultaneously casting the impressions forming such line.

9. In a type casting mechanism, a plurality of keys, a plurality of symbols upon each key, a plurality of shutters, one controlled by each key, a plurality of stops controlled by each shutter, a plurality of matrices adapted to be positioned by the stops, means for moving said matrices into position against said stops and means for positioning type forming material against the matrices.

10. In a type casting mechanism, a plurality of keys, a plurality of symbols upon each key, a plurality of shutters, one controlled by each key, a plurality of stops controlled by each shutter, a plurality of matrices adapted to be positioned by the stops, means for moving said matrices into position against said stops and means for positioning thereagainst the type forming material, a shift mechanism associated with said keys, and means, associated therewith, adapted relatively to move the stops and the shutters in response to actuation of said shift mechanism.

11. In a type casting mechanism, a typewriter key board, a plurality of symbols upon each key, a plurality of shutters, one controlled by each key, a plurality of stops controlled by each shutter, said stops being arranged in pairs, a plurality of matrices adapted to be positioned by the stops, each said pair of stops being aligned with one of said matrices, means for moving said matrices into position

sition against said stops and means for positioning thereagainst the type forming material, a typewriter shift mechanism associated with said keys, and shutter controlling means associated therewith and adapted to impart relative movement to said stops and shutters in response to actuation of said shift mechanism, one stop of each pair being positioned to be controlled by the shutters when in normal position and the other being positioned to be controlled by them when shifted.

12. In a type casting mechanism, a key board, a plurality of stops controlled by the key board, a plurality of matrices adapted to be positioned by the stops, a plurality of typewriter bars adapted to be actuated by the keys of the key board, an impression receiving member, and means for supporting it in opposition thereto, means for moving said matrices into position against said stops, and means for positioning type forming material against the matrices.

13. In a type casting mechanism, a key board, a plurality of stops controlled thereby, a plurality of matrices adapted to be positioned by the stops, each of said matrices having formed thereon a plurality of type impressions, a plurality of type bars adapted to be actuated by the keys of said board, an impression receiving member and means for supporting it in opposition thereto, means for moving said matrices into position against said stops, means for positioning type forming material against the matrices, and means, independent of the key board, for moving the stops into inoperative position.

14. In a type casting mechanism, a typewriter key board, a plurality of shutters, one controlled by each key, a plurality of stops controlled by each shutter, said stops being arranged in pairs, a plurality of matrices adapted to be positioned by the stops, each said pair of stops being aligned with one of said matrices, each matrix having formed thereon a plurality of type impressions, means for moving said matrices into position against said stops and means for positioning thereagainst the type forming material, a plurality of type bars adapted to be controlled by the key board, an impression receiving member and means for supporting it in opposition thereto, and means, independent of the key board, for moving the stops into inoperative position.

15. In a type casting mechanism, a typewriter key board, a plurality of shutters, one controlled by each key, a plurality of stops controlled by each shutter, said stops being arranged in pairs, a plurality of matrices adapted to be positioned by the stops, each said pair of stops being aligned with one of said matrices, each matrix having formed thereon a plurality of type impressions, means for moving said matrices into position

- against said stops and means for positioning thereagainst the type forming material, a plurality of type bars adapted to be controlled by the key board, an impression receiving member and means for supporting it in opposition thereto, and means, independent of the key board, for moving the stops into inoperative position, a typewriter shift mechanism associated with said keys, and 5 shutter controlling means associated therewith and adapted to impart relative movement to said stops and shutters in response to actuation of said shift mechanism, one stop of each pair of stops being positioned to be 10 controlled by the shutters when in normal position and the other being positioned to be controlled by them when shifted.
16. In a type casting mechanism, a key board, a plurality of stops controlled by the 20 key board, a plurality of matrices adapted to be positioned by the stops, each of said matrices having formed thereon a plurality of impressions, means for simultaneously moving a plurality of matrices into position 25 against the stops, and means for positioning type forming material against the matrices.
17. In a type casting mechanism, a key board, a plurality of stops separate from and controlled by the key board, a plurality of 30 matrices adapted to be positioned by the stops, each of said matrices having formed thereon a plurality of impressions, means for simultaneously moving a plurality of matrices into position against the stops, and 35 means for positioning type forming material against the matrices, and supplemental control means for said stops, independent of said key board, for returning said stops to inoperative position.
18. In a type casting mechanism, a key board, a plurality of stops controlled by the key board, a plurality of matrices adapted to be positioned by the stops, each of said matrices having formed thereon a plurality 40 of impressions, means for simultaneously moving a plurality of matrices into position against the stops, and means for positioning type forming material against the matrices, and supplemental control means for said 45 stops, independent of said key board, for returning said stops to inoperative position, comprising a roller and means for moving it along said stops.
19. In a type casting machine, a typewriter 50 adapted to write on a sheet, a stop bed separate from said typewriter containing a plurality of stops, means controlled by the typewriter for moving selected stops into working position, a plurality of matrix strips, 55 means for yieldingly moving them into engagement with said stops, a mold, one side of which is formed by said strips adapted to cast a type slug, means for distributing the matrix strips after the slug has been cast.
20. In a type casting machine, a typewriter 60 adapted to write on a sheet, a stop bed separate from said typewriter containing a plurality of stops, means controlled by the typewriter for moving selected stops into working position, a plurality of matrix strips, 65 means for yieldingly moving them into engagement with said stops, a mold, one side of which is formed by said strips adapted to cast a type slug, means for distributing the matrix strips after the slug has been cast, the operation of the typewriter and stop bed being independent of the operation of the other parts after the matrix strips have been brought into engagement with the stops. 70
21. In a type casting machine, a typewriter 75 adapted to write on a sheet, a stop bed separate from said typewriter containing a plurality of stops, means controlled by the typewriter for moving selected stops into working position, a plurality of matrix strips, 80 means for yieldingly moving them into engagement with said stops, a mold, one side of which is formed by said strips adapted to cast a type slug, means for distributing the matrix strips after the slug has been cast, the operation of the typewriter and stop bed being independent of the operation of the other parts after the matrix strips have been brought into engagement with the stops. 85
22. In a type casting machine, a plurality 90 of matrix members, a mold, means for selecting and positioning the members to form one side of the mold, a typewriter and a working connection between it and the selecting means whereby when the typewriter keys are depressed the typewriter will write proof and simultaneously control the selection of the matrix members and means for simultaneously casting a slug containing the impressions of the matrix members so selected and positioned. 95
23. In a type casting machine, a plurality 100 of matrix members, a mold, means for selecting and positioning the members to form one side of the mold, a typewriter and a working connection between it and the selecting means whereby when the typewriter keys are depressed the typewriter will write proof and simultaneously control the position of each matrix member and means for simultaneously casting a slug containing the impressions of the matrix members so selected and positioned. 110
24. In a type casting machine, a plurality 115 of matrix members, a mold, means for selecting and positioning the members to form one side of the mold, a typewriter and a working connection between it and the selecting means whereby when the typewriter keys are depressed the typewriter will write proof and simultaneously control the selection of the matrix members. 120
25. In a type casting machine, a typewriter 125 adapted to write on a sheet, a stop bed separate from said typewriter containing a plurality of stops, means controlled by the typewriter for moving selected stops into working position, a plurality of matrix strips, means for yieldingly moving them into engagement with said stops, a mold, one side of which is formed by said strips adapted to cast a type slug, means for distributing the matrix strips after the slug has been cast, the operation of the typewriter and stop bed being independent of the operation of the other parts after the matrix strips have been brought into engagement with the stops. 130

- matrix members, means for moving the matrix members, limiting their movement by the selecting mechanism and at one operation casting a single slug from all the matrix members.
25. In a type casting machine, a plurality of matrix members, a mold, means for selecting and positioning the members to form one side of the mold, a typewriter and a working connection between it and the selecting means whereby when the typewriter keys are depressed the typewriter will write proof and simultaneously control the position of each matrix member, means for moving the matrix members, limiting their movement by the selecting mechanism and at one operation casting a single slug from all the matrix members.
26. In a type casting machine, a plurality of matrix members, a mold, means for selecting and positioning the members to form one side of the mold, a typewriter and a working connection between it and the selecting means whereby when the typewriter keys are depressed the typewriter will write proof and simultaneously control the selection of the matrix members, means for moving the matrix members, limiting their movement by the selecting mechanism and at one operation casting a single slug from all the matrix members, the selecting means being adapted to operate for the selection of a successive arrangement of matrix means during the time that the casting is taking place.
27. In a type casting machine, a plurality of matrix members, a mold, means for selecting and positioning the members to form one side of the mold, a typewriter and a working connection between it and the selecting means whereby when the typewriter keys are depressed the typewriter will write proof and simultaneously control the position of each matrix member, means for moving the matrix members, limiting their movement by the selecting mechanism and at one operation casting a single slug from all matrix members, the selecting means being adapted to operate for the selection of a successive arrangement of matrix members during the time that the casting is taking place.
28. In a type casting machine, a plurality of matrix members, a mold, means for selecting and positioning the members to form one side of the mold, a typewriter and a working connection between it and the selecting means whereby when the typewriter keys are depressed the typewriter will write proof and simultaneously control the selection of the matrix members, means for moving the matrix members, limiting their movement by the selecting mechanism and at one operation casting a single slug from all the matrix members, the selecting means being adapted to operate for the selection of a successive

arrangement of matrix means during the time that the casting is taking place, and means for distributing the matrix members after casting has taken place independent of the selecting means.

29. In a type casting machine, a mold, a plurality of matrix elements, adapted to be presented to the mold for casting, means for selecting characters on said elements and placing them in register with the mold, a typewriter and means controlled thereby for controlling the character selecting means so that the character presented to the mold are the same as those written by the typewriter and means for simultaneously casting from the matrix members so selected and positioned.

30. In a type casting machine, a typewriter, a plurality of movable matrix elements, a mold, means for presenting selected characters on said elements into register with the mold, means controlled by the typewriter for selecting said characters and means for simultaneously casting from the matrix members so selected and positioned.

31. In a type casting machine, a mold, a plurality of matrix elements having characters thereon, a typewriter, means responsive to the actuation of the typewriter for presenting selected characters into register with the mold and means for simultaneously casting from the matrix members so selected and positioned.

32. In a type selecting machine, a typewriter unit, a key extension engaged by each typewriter key, guide means therefor and a type selecting mechanism controlled thereby, the key extensions being adapted to remain in working relation with the balance of the mechanism when the typewriter unit is removed.

33. In a type selecting machine, a typewriter unit, a key extension engaged by each typewriter key, guide means therefor, including the typewriter comb plate.

34. In a type selecting machine, a typewriter unit, a key extension engaged by each typewriter key, guide means therefor including a guide plate carried by the machine frame.

35. In a type selecting machine, a typewriter unit, a key extension engaged by each typewriter key, guide means therefor comprising the typewriter comb plate and a guide plate mounted on the machine frame.

36. In a type selecting machine, a typewriter unit, a key extension engaged by each typewriter key, a lever upon which the key extension is pivoted, a type selecting mechanism and a connection between it and the lever.

37. In a type selecting machine, a typewriter unit, a key extension engaged by each typewriter key, a lever upon which the key extension is pivoted, a type selecting mechanism and a connection between it and the lever.

lever, and guide means for the key extension removed from the lever.

38. In a type selecting machine, a typewriter unit, a key extension engaged by each typewriter key, a lever upon which the key extension is pivoted, a plurality of pivoted shutters and a connection between each of them and one of the levers.

39. In a type selecting machine, a typewriter unit, a key extension engaged by each typewriter key, a lever upon which the key extension is pivoted, a plurality of pivoted shutters and a connection between each of them and one of the levers, and yielding means for returning each shutter to its original position after the pressure on the key has been released.

40. In a type selecting machine, a typewriter unit, a key extension engaged by each typewriter key, a lever upon which the key extension is pivoted, a plurality of pivoted shutters and a connection between each of them and one of the levers comprising ears on the shutters and a tension member interposed between each ear and a lever.

41. The combination with a typewriter having a plurality of keys, and a plurality of character elements, each key controlling a plurality of said characters, of a matrix having thereon the characters of said keyboard, the characters controlled by each key being positioned adjacently on said matrix, a character controlled by one of said keys being omitted from the matrix, the other character controlled by said key being positioned at one end of the matrix.

42. The combination with a typewriter having a plurality of keys, and a plurality of character elements, each key controlling a plurality of said characters, of a matrix having thereon the characters of said keyboard, the characters controlled by each key being

positioned adjacently on said matrix, the characters inapplicable to type casting being omitted from said matrix.

45

43. The combination with a typewriter having a plurality of keys, and a plurality of character elements, each key controlling a plurality of said characters, of a matrix having thereon the characters of said keyboard, the characters controlled by each key being positioned adjacently on said matrix, the characters inapplicable to type casting being omitted from said matrix, the characters controlled by keys controlling said omitted characters being positioned adjacent the ends of the matrix.

55

44. In a type casting mechanism, a keyboard, a fixed stop bed, a plurality of stops controlled by the keyboard, a plurality of parallel matrix bars slidably mounted beneath the stop bed and adapted to be positioned by the stops, means for moving said matrix bars into position in relation to said stops, and means for positioning type forming material against the matrices.

65

45. In a type casting mechanism, a keyboard, a fixed stop bed, a plurality of stops controlled by the keyboard, a plurality of parallel matrix bars slidably mounted beneath the stop bed and adapted to be positioned by the stops, each such matrix bar having formed thereon, in longitudinal alignment, a plurality of intaglio impressions corresponding to the characters appearing on the keyboard, the characters controlled by each key being adjacently positioned on the bars, means for moving said matrix bars into position in relation to said stops, and means for positioning type forming material against the matrices.

75

Signed at Chicago, county of Cook and State of Illinois, this 17th day of April, 1925.

CHESTER A. MACOMIC.
